2 SHEETS—SHEET 2.

UNITED STATES PATENT OFFICE.

WALTER C. POLK, OF CHICAGO, ILLINOIS, ASSIGNOR TO POLK-GENUNG-POLK CO., OF FORT BRANCH, INDIANA, A CORPORATION OF INDIANA.

CONCRETE-CONSTRUCTION APPARATUS.

Application filed August 1, 1919. Serial No. 314,598.

To all whom it may concern:

Be it known that I, WALTER C. POLK, a citizen of the United States, residing at Chicago, in the county of Cook and State 5 of Illinois, have invented a new and useful Concrete-Construction Apparatus, of which the following is a specification.

It is the object of my invention to provide an apparatus for constructing circular 10 concrete structures, such as silos; and to make such apparatus simple in structure, easy to handle, and readily adaptable to structures of different size.

The accompanying drawing illustrates 15 my invention: Fig. 1 is a perspective view of a partly built silo in process of construction by the use of apparatus embodying my invention; Fig. 2 is a partial plan of one of the plates which I mount on the 20 central mast; Fig. 3 is a perspective view of the inner end of one of the radius bars; Fig. 4 is a perspective view of the outer end of one of the radius bars, connected to the 25 adjacent parts of two segments of the inner form; Fig. 5 is a view similar to Fig. 4, showing the connection between the radius bar and the inner forms at a point of tightening the segments; Fig. 6 is a perspective 30 view showing the interlocking connection between segments of the outer forms; Fig. 35 7 is a plan of the mast and the cross beam pivotally mounted thereon; Fig. 8 is a section on the line 8—8 of Fig. 5; Fig. 9 is a perspective view of one of the spacers between inner and outer forms; and Fig. 10 is a perspective view of one of the radius bars.

The silo 10 or other structure to be constructed may be provided with any suitable 40 opening or openings 11, one near the bottom being shown. In constructing the silo or other structure, I first set up a mast 12, extending vertically along the vertical axis of the proposed silo, and support it by suitable guy wires 13. Mounted on this mast 45 12 are a number of attaching plates 14, the number of which depends upon the height of the proposed silo. These plates 14 may be slid along the mast 12 and supported at 50 any desired heights thereon by cross pins

extending through transverse holes 15 in the mast. Ordinarily, two of these plates 14 are in use at any one time, and those above rest as a group on a cross pin and are brought successively into use from bottom 55 to top as the silo increases in height, leaving a group of plates of constantly diminishing number above the working plates, and each plate conveniently being allowed to drop to the bottom of the mast when its 60 work has been finished.

Each plate 14 is provided with a plurality of pairs of annular series of holes, being shown as having three pairs of such series. Each pair comprises an inner series 65 of rectangular holes 16 and an outer series of circular holes 17, such outer holes 17 being radially in line with the corresponding inner holes 16. Each rectangular hole 16 may co-operate with a curved finger 18, 70 of rectangular cross section, projecting upward from a metal fitting 19 at the inner end of a radius bar 20; and each hole 17 may co-operate with an upwardly projecting pin 21 also projecting upward from the 75 fitting 19 and spaced from the curved finger 18 similarly to the spacing between corresponding holes 16 and 17, so that when the curved finger is threaded through the hole 16 with the radius bar 20 oblique, and such 80 radius bar is then brought up to the horizontal position, the pin 21 will project through the hole 17 to provide a positioning interlock between the radius bar and the plate 14. The number and the length 85 of the radius bars 20 which are used in the construction of the silo depends upon the diameter of the silo, such bars being adjustable in length as shown in Fig. 10; and it is because of this variability in the number 90 of the radius bars that the plurality of pairs of series of holes 16 and 17 are provided. The number of holes in each pair of annular series corresponds to some desired number of radius bars, for silos of 95 certain diameters. It is found that three sizes cover all those most commonly in use, so that ordinarily it is only necessary to provide three pairs of series of holes.

The outer end of each radius bar 20 is pro- 100

vided with a fitting 22 or 23 (see Figs. 4 and 5) which is vertically grooved at its outer ends to receive the adjacent inwardly projecting parts of two vertical angle bars 24 attached to and stiffening the abutting edges of two inner form segments 25. These form segments are of sheet metal, stiffened at all four edges by angle bars 24. They are of such length circumferentially that they span the space between the outer ends of adjacent radius bars 20, and meet at such radius bars; and they are preferably slightly curved so as to conform to the general curvature of the circle of the inner surface of the proposed silo. They may be made to conform exactly for one diameter of silo, but they will come sufficiently close to conformity for the other diameters so that the difference is not noticeable. The number of segments 25 for any sizes of silo will correspond to the number of radius bars 20 and to the number of pairs of holes 16 and 17 in the pair of series of holes 16 and 17 being used for that size of silo. The angle bars 24 at the vertical meeting edges of the plates 25, as stated, project into grooves in the vertical outer edges of the fittings 22 or 23, and are held there by cross pins 26, which may be ordinary nails, which extend through mating holes 27 in such angle bars 24 and fittings 22 or 23. The grooves in the fittings 22 are merely sufficiently wide to receive the two inwardly projecting parts of the vertical angle bars 24. The grooves in the fittings 23, however, are wider, and in addition to receiving the inwardly projecting parts of the vertical angle bars 24 they also receive a pair of oppositely facing wedges 28 located between such inwardly projecting flanges and serving to spread them apart, to permit loosening of the series of inner forms when taking them down; the wedges 28 at one edge are flush with the concrete-abutting surfaces of the inner forms 25.

In addition to the inner forms 25, for the inner surface of the silo wall, there are outer forms made up of segments 30, which are preferably of the same height as the segments 25. These outer form segments 30 are provided at their four edges with stiffening angle bars 31, which in their outwardly projection parts have holes 32 which mate with similar holes in the angle bars at the meeting edges of adjacent segments 30—above, below, or on either side—so that through these mating holes pins 33 may be projected. There are similar mating holes 32 in the inwardly extending flanges of the angle bars 24. A bifurcated hooked clamp 34 receives in the opening between its two prongs the projecting flanges of the meeting angle bars 31 or 24, and the ends of the prongs of such clamp are provided with hooks which extend around the pin 33, as is

clear from Fig. 6; so that by hooking the clamp 34 on the pin 33 and then turning the clamp the pin 33 is held in place and the two meeting angle bars are held together. This interlock takes place at both horizontal and vertical meeting edges of the outer form segments 30, and also at the horizontal meeting edges and at the lower parts of the vertical meeting edges of the inner form segments 25. The inner and outer forms may be spaced apart by spacers 35, (see Fig. 9,) conveniently formed of sheet metal with the corners cut out and the lateral edges bent downward to project between such inner and outer form segments, the ends of such spacers resting on the upper edges of such form segments; these are only used at the upper edges of the series of forms, and may be removed as the concrete approaches such upper edges, conveniently being provided with holes 36 through which vertical reinforcing rods may pass.

A cross-beam 40, conveniently a T-iron inverted, is pivotally mounted at its center on the mast 12, and is connected by upright bars 41 to an upper bearing 42 joined by guy wires 43 to the cross beam 40. A trolley 44 travels on the upper edge of the stem of the T-iron forming the beam 40, and the depending bail 45 from this trolley is provided with a hook 46 which may carry a dump-bucket 47. The two ends of the cross-beam 40 are provided with pulleys 48, over which and over a pulley 49 attached to a post 50 in the ground extends a cable 51 which is attached to the bail of the bucket 47 so that by manipulating the cable 51 such bucket 47 may be raised to the hook 46 or lowered to the ground to be filled. The cable 51 where it extends between the two pulleys 48 at the ends of the cross-beam passes to the side of the mast 12, and tends to bow the cross-beam sidewise; and to resist this, while still permitting a slight bowing so that the cable will not rub the mast, the cross beam is provided with a tension brace 52 extending around the mast 12 on the opposite side from the cable 51 and attached to two points on the cross-beam 40 on opposite sides of such mast to resist such bowing tendency. This tension brace has a turn buckle 52' by which the bowing of the cross-beam may be controlled.

In the use of my apparatus, the mast 12 is first set up with a sufficient number of plates 14 thereon. Radius bars 20 of sufficient number are attached to the lowermost plate 14, which rests on a cross pin in a hole 15 in the mast 12, and the outer ends of such radius bars are then attached to the lowermost series of inner form segments 25, which are held together by the fittings 22 and 23 at such outer ends and by pins 33 and clamps 34, and the wedges 28 are put in place. Then the lowermost series of outer

segments 30 are set in place around the inner segments and suitably spaced therefrom by the spacers 35, adjacent outer form segments being suitably fastened together 5 by the pins 33 and clamps 34. When an opening 11 is desired, a suitable form to give such opening the proper shape is placed between the inner and outer form segments. Then the space between the inner and outer 10 form segments is filled with concrete, which for the lower form segments may be put in place by hand but which is lifted by the bucket 47 and cable 51 as the silo increases in height and carried by the trolley 44 and 15 hook 46 inward along the cross beam 40 to the proper place so that by dumping the bucket 47 the concrete is caught in a hopper chute 53 discharging into the space between the inner and outer forms. When the space 20 between any lower series of inner and outer forms has been filled, and suitably tamped, the next higher series of segments may be put in place in this same way, and attached to the adjacent lower form segments by pins 25 33 and clamps 34. When the space between this second set of forms is filled, the first set of forms, both inside and outside, may be removed, the wedges 28 being first removed to permit the removal of the inner forms, 30 and their radius bars disconnected from the associated plate 14 and such plate allowed to drop to the bottom of the mast; and then these removed forms may be set on top of the forms which previously were on top of 35 them, the radius bars 20 being associated with the lowermost of the waiting group of plates 14. This may be continued until the silo has reached the desired height, each set 40 of form segments being removed when the set above it has been filled and then being placed above the set which was previously above it, but with a different attaching plate 14. The forms of either set, for only two sets are necessary, though more can be used, 45 may be removed from below a higher set without disturbing the latter and then placed above such formerly higher set, still without disturbing it. It thus becomes possible to build a silo of any desired height in 50 a simple and rapid manner, with a minimum expenditure for forms; and the same forms may be used for silos of several different sizes, both inner and outer sets of forms conforming sufficiently closely in curvature to 55 the true circles corresponding to such silos so that the difference is not noticeable for the usual variations in diameter of silos.

I claim as my invention:

1. In an apparatus for constructing circular concrete buildings, the combination of a central mast, a plurality of plates greater than two encircling said mast and slidably along it to any desired position, two sets of radius bars which may be connected with 60 said plates, two annular series of inner form members associated with the outer ends of said radius bars, and two annular series of outer form members spaced from said inner form members, the number of said mast plates being greater than the number of sets 70 of radius bars and greater than the number of series of inner or outer form members, so that as the building progresses lower series of inner and outer form members and the radius bars of the lower series of inner 75 form members may be removed from below the higher series and put in place above such formerly higher series in connection with a higher plate on the mast.
2. In an apparatus for constructing circular concrete buildings, the combination of a central mast, a plurality of plates carried by said mast, two sets of radius bars which may be connected with said plates, two annular series of inner form members associated with the outer ends of said radius bars, and two annular series of outer form members spaced from said inner form members, so that as the building progresses lower series of inner and outer form members and the radius bars of the lower series of inner 85 form members may be removed from below the higher series and put in place above such formerly higher series in connection with a higher plate on the mast, said 90 inner form members having inwardly projecting flanges at their vertical edges and the outer ends of said radius bars having grooves each receiving two such inwardly projecting flanges of two inner form members meeting 95 at the outer end of such radius bars.
3. In an apparatus for constructing circular concrete buildings, the combination of a central mast, a plurality of plates carried by said mast, two sets of radius bars which may be connected with said plates, two annular series of inner form members associated with the outer ends of said radius bars, two annular series of outer form members spaced from said inner form members, so that as the building progresses lower 105 series of inner and outer form members and the radius bars of the lower series of inner form members may be removed from below the higher series and put in place above such formerly higher series in connection with a higher plate on the mast, said inner form members having inwardly projecting flanges at their vertical edges and the outer 110 ends of said radius bars having grooves each receiving two such inwardly projecting flanges of two inner form members meeting 115 at the outer end of such radius bars, and cross pins for connecting said inwardly projecting flanges and said radius bars.
4. In an apparatus for constructing circular concrete buildings, the combination of a central mast, radius bars having their inner ends supported from said mast, and an annular series of inner form members, said 120 125 130

inner form members having inwardly projecting flanges at their meeting edges and the outer ends of said radius bars having grooves each receiving two meeting inwardly projecting flanges of adjacent inner form members.

5. In an apparatus for constructing circular concrete buildings, the combination of a central mast, a plurality of plates mounted 10 on said mast, each of said plates having a plurality of annular series of attaching holes with different numbers of holes in said series, radius bars which may be attached to said plates at any of said annular series 15 of holes according to the number and length of the radius bars, and inner form members associable with the outer ends of said radius bars.

6. In an apparatus for constructing circular concrete buildings, the combination of 20 a central mast, a plurality of plates mounted on said mast, each plate having two series of annular holes, radius bars each provided at its inner end with an upwardly curved finger for extending through a hole of one set and with a projection which engages with a corresponding hole of the other set when the radius bar is brought to horizontal 25 position, and inner form members associated 30 with the outer ends of said radius bars.

7. In an apparatus for constructing circular concrete buildings, the combination of a central mast, radius bars having their inner ends supported from said mast, an annular series of inner form members, said inner form members having inwardly projecting flanges at their meeting edges and the outer ends of said radius bars having grooves each receiving two meeting inwardly 40 projecting flanges of adjacent inner form members, the groove in the outer end of one of said radius bars being wider than two such inwardly projecting flanges, and wedges arranged to be removably placed into 45 said wider groove to spread the adjacent inner form members.

8. In an apparatus for constructing circular concrete buildings, the combination of a central mast, radius bars having their inner ends supported from said mast, an annular series of inner form members, said inner form members having inwardly projecting flanges at their meeting edges and the outer ends of said radius bars having 50 grooves each receiving two meeting inwardly projecting flanges of adjacent inner form members, and cross pins for attaching together the outer ends of said radius bars and the associated inwardly projecting flanges.

60 9. In an apparatus for constructing circular concrete buildings, the combination of a central mast, a plurality of series of inner form members, means for spacing said inner form members from the mast, a plurality of 65 sets of outer form members spaced from the

inner form members, said form members being provided at their meeting edges with flanges which project away from the form members of the other set and are provided with transverse holes, pins projectible 70 through such holes of meeting flanges, and hooked bifurcated clamping members arranged to be placed astride said meeting flanges and to hook around the ends of said pins.

75 10. In an apparatus for constructing circular concrete buildings, the combination of a central mast, a plurality of series of inner form members each provided at all four edges with inwardly projecting flanges, 80 radius bars grooved at their outer ends to receive meeting flanges of adjacent form members of a series, said radius bars being detachably associated with said mast, and means for clamping the meeting flanges of 85 form members of one series to the meeting flanges of the adjacent members of the other series, so that either series may be removed without disturbing the other.

90 11. In an apparatus for constructing circular concrete buildings, the combination of a central mast, a plurality of plates carried by said mast, two sets of radius bars which may be connected with said plates, two annular series of inner form members associated with the outer ends of said radius bars, two annular series of outer form members spaced from said inner form members, so that as the building progresses lower series of inner and outer form members and 100 the radius bars of the lower series of inner form members may be removed from below the higher series and put in place above such formerly higher series in connection with a higher plate on the mast, said inner form members having inwardly projecting flanges at their vertical edges and the outer ends of 105 said radius bars having grooves each receiving two such inwardly projecting flanges of two inner form members meeting at the 110 outer end of such radius bars, and wedges associated with the meeting edges of two adjacent inner form members for spreading them apart.

115 12. In an apparatus for constructing circular concrete buildings, the combination of a central mast, radius bars having their inner ends supported from said mast, an annular series of inner form members, said inner form members having inwardly projecting flanges at their meeting edges and the outer ends of said radius bars having grooves each receiving two meeting inwardly 120 projecting flanges of adjacent inner form members, and wedges associated with the 125 meeting edges of two adjacent inner form members for spreading them apart.

13. In an apparatus for constructing concrete buildings, the combination with a central mast, of a cross beam mounted at its 130

center on said mast and extending therefrom in two directions, pulleys at the ends of said cross beams, a lifting cable passing over said pulleys to lift building material, said cable 5 extending the length of said beam and passing said mast, said cross beam being bowed at its center to permit said cable to extend

in a right line direction from end to end of the beam and clear said mast.

In witness whereof, I have hereunto set 10 my hand at Indianapolis, Indiana, this fifth day of June, A. D. one thousand nine hundred and nineteen.

WALTER C. POLK.
